ATTORNEY

UNITED STATES PATENT OFFICE.

DYER W. PERRY, OF KEENE, NEW HAMPSHIRE.

DESIGN FOR AN ADVERTISING-TAG.

SPECIFICATION forming part of Design No. 30,753, dated May 16, 1899.

Application filed April 22, 1899. Serial No. 714,111. Term of patent 14 years.

To all whom it may concern:

Be it known that I, DYER W. PERRY, a citizen of the United States, residing at Keene, in the county of Cheshire and State of New Hampshire, have invented and produced a new and original Design for Advertising-Tags or Similar Articles, of which the following is a specification, reference being had to the accompanying drawing, forming part thereof.

10 The figure in the drawing is a plan view of a tag, showing my new design.

The leading feature of my design consists, essentially, of the peculiar configuration of the body *a* of the tag or other article and the inwardly-extending arms *b* and *c*. The body

a is approximately shield shape, and the arms *b* and *c*, projecting from opposite corners, curve inwardly toward each other, the ends of said arms being separated from each other by a narrow space.

20

Having thus described my invention, I claim—

The design for a tag, or similar article, as herein shown and described.

In testimony whereof I affix my signature 25 in the presence of two witnesses.

DYER W. PERRY.
